[57] CLAIM

The ornamental design for a combination boat side steps and locker, as shown and described.

DESCRIPTION

FIG. 1 is a perspective front and left side view of a combination boat side steps and locker showing my new design;

FIG. 2 is a perspective view of the right and rear sides thereof;

FIG. 3 is a front elevation view thereof;

FIG. 4 is a right side elevation view thereof, the left side elevation view being a mirror image thereof; and,

FIG. 5 is a rear elevation view thereof.
